PROCESS FOR PREPARING PETROLEUM SULFONATES

Jere C. Showalter, Goose Creek, Tex., assignor to
Standard Oil Development Company, a corpora-
tion of Delaware

Application August 21, 1944, Serial No. 550,395

3 Claims. (CL 260—504)

1

The present invention is directed to a process for preparing water-soluble alkali metal sulfonates. More particularly, it is directed to the preparation of petroleum sulfonates which may be used in soft or hard water or in sea water. These sulfonates do not leave a deposit of gummy residues or foreign bodies on the object being cleansed, and are particularly suitable for use as a shampoo.

It is well known to produce sulfonic acids and salts of sulfonic acids of varying properties by treating mineral or petroleum oils with sulfuric acid of sulfonating strength and subsequently neutralizing the sulfonic acids with an alkali to obtain sulfonates suitable for use as detergents and cleansing agents.

In accordance with the present invention, I propose to prepare water soluble salts of sulfonates having novel characteristics by selecting the petroleum fraction to be sulfonated, by controlling the conditions of sulfonation and by employing a particular sequence of steps in cleansing the sulfonic acids. By the careful control of the steps of the process, I am able to obtain a metal salt of sulfonic acid readily soluble in water and appearing as a clear, light colored, aqueous solution, free from contaminating solid bodies and capable of being used as a detergent without leaving an undesirable residue on the object being cleansed.

The present invention will now be described in conjunction with the drawing, in which the sole figure is in the form of a flow sheet, diagrammatically illustrating the process of the present invention.

A distillate fraction having a viscosity in the range of 75 to 85 seconds Saybolt at 100° F. and obtained by fractionation of a naphthenic crude oil is passed via inlet 11 into a solvent extraction unit 12, where it is contacted with phenol as the selective solvent under conditions to form a raffinate fraction and an extract fraction. The step of solvent extraction with selective solvents is well known to the art, and for this reason the operating conditions in this unit will not be described in detail. It will be sufficient to say that usually the extract will have approximately 35% of the volume of the original distillate and the raffinate will comprise the remaining 65% of the distillate. The raffinate may be discarded from the solvent extraction unit via outlet 13 and the extract may be withdrawn through line 14 to acid treating unit 15. It will be understood that the unit designated by numeral 12 as the solvent extraction unit will include suitable distillation columns for

2

recovery of the solvent employed and that the extract indicated as being removed from the unit via line 14 will be substantially free from selective solvent.

5 In acid treating unit 15 the extract is admixed with 98% sulfuric acid in amounts ranging from 300 to 400 pounds of acid per barrel of extract. In the acid treating step approximately 50% of the extract is converted to sulfonated oil. The 10 sulfonating step is preferably carried out with the extract and sulfuric acid initially at atmospheric temperatures, and the maximum temperature of the reactants increasing to a temperature in the range of 120° to 170° F. as the sulfonation 15 reaction proceeds.

From unit 15 the mixture of reactants is withdrawn by line 17 to settler 18, where the reactants separate into a lower sludge layer, which is removed via line 19, and an upper layer of sulfonated oil, which is removed through line 20. To the sulfonated oil flowing through line 20 is added water via inlet 21 in an amount ranging from 3% to 5% of the sulfonated oil, and the two components are then passed through mixing device 9 to cause the thorough admixture of water with the sulfonated oil and the mixture is then passed through line 16 to a second settling vessel 22. The addition of the water to the mixture causes a separation to take place in settler 22 with sulfonic acids and water, in addition to entrained oil, settling as a bottom layer and unconverted oil separating as a top layer. The unconverted oil is withdrawn from the upper portion of settler 22 via line 23 and discarded from 30 the system. The sulfonic acids, water and oil entrained therein settling in the lower portion of vessel 22 are withdrawn via line 24.

To the mixture flowing in line 24 is added an alkali metal hydroxide via inlet 25 in an amount 40 sufficient to neutralize the sulfonic acids. It is preferred to employ either sodium or potassium hydroxide and to add an amount just sufficient to neutralize the sulfonic acids and convert them to sulfonic soaps. It will usually be found desirable to pass the mixture of sulfonic acids and alkali metal hydroxide through mixer 26 in order to insure a thorough admixture of the components. While a series of baffles have been indicated in the schematic mixer shown in the drawing, it will be understood that a vessel provided with a mechanical stirrer may be employed and the mixture maintained in the vessel until the sulfonic acids have been neutralized with the hydroxide.

65 The solution of sulfonic soaps is withdrawn

from mixer 26 and is treated for the removal of impurities therefrom. These impurities will usually include unreacted oil and water-insoluble sulfonates, as well as foreign bodies which may have been present in the feed or may have been picked up in the apparatus. The material from mixer 26 passes through line 27 and isopropyl alcohol is added thereto via line 28. It is desirable to use isopropyl alcohol commonly known as 50% alcohol, that is, 50% of the alcohol diluted with 50% of water, and in an amount of one volume of the alcohol solution to one volume of the sulfonic soap solution. The constituents in line 27 are then passed into mixer 29, where they are thoroughly admixed. The mixture is removed by line 30, where light hydrocarbon material is added by inlet 31 and then passed through a mixer 32 and line 33 into settling vessel 34. A number of light hydrocarbon fractions are suitable in the use of this extraction step. For example, liquefied propane, butane or pentane fractions may be used as well as higher boiling fractions, such as hexane or light naphtha or liquid mixtures including these constituents. It will usually be desirable to employ a light naphtha as the light hydrocarbon and to employ one volume of the light hydrocarbon to two volumes of the alcohol-sulfonic soap solution. The addition of the isopropyl alcohol and light hydrocarbon to the aqueous sulfonic soap solution causes the segregation of the oil and light hydrocarbon as one fraction and the alcohol and aqueous soap solution as another fraction, and these two fractions are separated by settling in unit 34. The oil and light hydrocarbon separates as an upper layer and is removed from unit 34 via outlet 35, and may be discarded. The lower layer, comprising alcohol and sulfonic soap solution, is withdrawn through outlet 36 to a distillation column 37, where the alcohol is vaporized and removed as overhead via outlet 38.

The alcohol-free sulfonic soap solution is withdrawn from the lower portion of the distillation tower 37 through line 39 and sent to a settling vessel 40, where it is allowed to settle for a substantial interval of time to separate a minor water-insoluble soap fraction from the remaining portion of the solution. It will be found desirable to allow the solution to remain in settler 40 in a quiescent state for an interval of time of the order of 24 hours. After the mixture in unit 40 has settled to form an insoluble soap fraction and a soluble soap fraction, the soluble soaps may be withdrawn as indicated through outlet 41 and the insoluble soaps may be withdrawn from the bottom of the vessel through outlet 42. Under some conditions the settling step in unit 40 may not remove all of the solids from the soluble soaps, and under such conditions it may be desirable to pass the water-soluble soaps via line 41 through filter 43 in order to obtain a purified water-soluble sulfonate solution. However, the settling step may separate substantially all of the solid materials from the water-soluble soaps, and if such be the case the filter may be bypassed by line 44. Valve 43' is indicated for controlling the flow through filter 43 and valve 44' for controlling the flow through bypass line 44. The purified aqueous solution of alkali metal salts of sulfonates may be passed either through filter 43 or bypass line 44 into outlet line 45, from which they may be withdrawn to suitable storage facilities, not shown.

The aqueous solution in line 45 is free from harsh alkalies and solid materials and is suitable for use as a detergent. The aqueous solution has been found suitable for use as a shampoo, and for

such use it is desirable to employ a mixture comprising 15% of the alkali metal sulfonates and 85% water. The water content of the solution may, of course, be readily controlled, but for purposes of illustration the addition of water thereto for controlling the concentration of the solution is indicated by inlet line 46.

The aqueous solution of water-soluble alkali metal sulfonates has a pH of 7 and is free from contaminating materials and solids which would be undesirable in a detergent material. The alkali metal salts of the sulfonates are readily soluble in water, and it is, therefore, unnecessary to employ a vehicle or solvent, such as alcohol, in the solution in order to maintain the sulfonate salt in solution.

It is to be emphasized that the washing steps and settling steps in the described process are necessary in order to obtain a detergent material having the characteristics given above. The omission of any of these steps results in a product which is not free from solids and gummy constituents and is unsuitable for use as a detergent in shampoos and like compositions. As stated above, the final filtering step illustrated is optional and may be omitted in case satisfactory settling is obtained in the preceding vessel.

Having fully described the present invention, what I desire to claim is:

1. A method for producing a detergent suitable for use as a shampoo comprising the steps of extracting a naphthenic distillate having a viscosity in the range of 75 to 85 seconds Saybolt at 100° F. with a selective solvent under conditions to form a raffinate and an extract, contacting the extract with concentrated sulfuric acid in the range of 300 to 400 pounds of acid per barrel of extract under conditions to form a sludge layer and a sulfonated oil layer, separating the sludge layer, adding from 3% to 5% of water to the sulfonated oil layer and settling to produce an oil layer and a sulfonic acid layer, withdrawing the sulfonic acid layer and contacting it with a solution of an alkali metal hydroxide to form a soap, mixing the soap with isopropyl alcohol, extracting the mixture with a light hydrocarbon, distilling the extracted soap to remove alcohol and light hydrocarbon therefrom and settling to form a layer of water-insoluble soap and a layer of water-soluble soap and removing the water-soluble soap as product.

2. A method for producing a detergent suitable for use as a shampoo comprising the steps of extracting a naphthenic distillate having a viscosity in the range of 75 to 85 seconds Saybolt at 100° F. with a selective solvent maintained under conditions to form a raffinate and an extract, separating the extract from the raffinate and contacting it with 98% sulfuric acid in the amount of from 300 to 400 pounds of acid per barrel of oil and at a temperature in the range of atmospheric to 170° F. to form a sludge layer and a sulfonated oil layer, removing the sludge layer, adding from 3% to 5% of water to the sulfonated oil layer and settling to obtain an oil layer and a sulfonic acid layer, withdrawing the sulfonic acid layer and contacting it with a solution of an alkali metal hydroxide to form a soap, adding isopropyl alcohol to the soap to form an admixture, extracting the admixture with a light hydrocarbon, distilling the extracted mixture to remove alcohol and light hydrocarbons therefrom, and subsequently settling to form a layer of water-insoluble soap and a layer of water-soluble soap

and removing the water-soluble soap as product.

3. A method for producing a detergent suitable for use as a shampoo comprising the steps of extracting a naphthenic distillate fraction having a viscosity in the range of 75 to 85 seconds Saybolt at 100° F. with a selective solvent maintained under conditions to form an extract having approximately 35% of the volume of the original distillate and a raffinate, separating the extract from the raffinate and admixing therewith 98% sulfuric acid in amounts ranging from 300 to 400 pounds of acid per barrel of extract and at a temperature in the range of atmospheric to 170° F. to form a sulfonated oil portion comprising approximately 50% of the extract and a sludge portion, settling to form a sludge layer and a sulfonated oil layer, removing the sulfonated oil layer, adding from 3% to 5% water thereto and settling to form an oil layer and a sulfonic acid

5 layer, withdrawing the sulfonic acid layer and contacting it with a solution of alkali metal hydroxide in an amount sufficient to neutralize the sulfonic acid layer and form a soap, mixing the resulting soap with an equal volume of isopropyl alcohol, adding to the mixture of soap and isopropyl alcohol a light hydrocarbon in the amounts of 2 volumes of soap alcohol mixture to 1 volume of a light hydrocarbon and subsequently settling to obtain a light hydrocarbon layer, an alcohol aqueous and soap solution layer, removing the alcohol and aqueous soap solution layer and distilling to remove alcohol therefrom, removing alcohol-free sulfonic soap solution from the distillation step and settling to form a layer of water-insoluble soap and a layer of water-soluble soap as product.
